UNITED STATES PATENT OFFICE.

EMIL EINFELDT, OF DAVENPORT, IOWA, ASSIGNOR TO BETTENDORF METAL WHEEL COMPANY, A CORPORATION OF IOWA.

TRACTION-WHEEL.

No. 852,831.

Specification of Letters Patent.

Patented May 7, 1907.

Application filed December 6, 1906. Serial No. 346,578.

To all whom it may concern:

Be it known that I, EMIL EINFELDT, of Davenport, county of Scott, and State of Iowa, have invented a new and useful Improvement in Traction-Wheels, of which the following is a specification.

This invention relates to traction wheels, and has reference more particularly to the form and construction of the traction cleats, and their manner of application to the wheel rim.

The invention consists in complementary cleats, embodying each a base flange adapted to be seated and secured to the rim of the wheel, and a vertical flange or web to serve as a traction surface, the said cleats being so applied that the vertical flanges or webs will conjointly form a continuous and uninterrupted traction surface extending zigzag around the rim.

The invention consists also in the details of construction and combination of parts hereinafter described and claimed.

In the accompanying drawings:—Figure 1 is a side elevation of a portion of a wheel having my invention embodied therein. Fig. 2 is a top plan view of the same partly in section. Fig. 3 is a transverse section on the line *a—a* of Fig. 2. Figs. 4 and 5 are side elevations of two of the cleats detached, showing their relative forms by which they are adapted to coöperate in accordance with my invention. Fig. 6 is a plan view of a portion of the rim of a wheel, showing the traction cleats applied in a modified and different manner.

Referring to the drawings:—1, 2, 3, etc., represent my improved traction cleats, each in the form of a length of commercial angle steel, having a base flange A and an upright web or flange B, the base flange being adapted to rest on and be secured to the rim of the wheel, while the upright flange serves as a traction rib or surface. These cleats are applied to the rim in such manner and in such relative arrangement, that conjointly the vertical flanges will present an uninterrupted and continuous traction rib or surface extending zigzag around the wheel rim. As shown, the cleats extend obliquely at relative angles, the base flanges being overlapped in order that the vertical flange of one cleat may be brought close up to and form an angular continuation of the vertical flange of the next cleat. In the overlapping of the ends of the cleats, each cleat has its base flange at

one end overlying the base flange of one of its adjacent cleats, while the opposite end of its base flange underlies the base flange of its other adjacent cleat. This arrangement is clearly illustrated in Fig. 2, where it will be seen that the forward end (assuming for the purposes of description that the wheel is traveling to the right) of cleat 2 rests upon and overlies the rear end of cleat 3 in advance, while the rear end of cleat 2 underlies and extends beneath the forward end of cleat 1 at the rear.

In order that in the arrangement described the upper edges of the vertical flanges will be on the same level, that is flush with each other, notwithstanding the overlapping of the ends, I form the base flange of each cleat at one end with a socket or bend in its underside to receive the base flange of the cleat upon which it is seated, the result being that when the cleats are assembled and the bend or socket portion of each rests on the base flange of the next cleat, the upper edge of the vertical flange of the socketed cleat will be at the same level or flush with and will adjoin the upper edge of the vertical flange of the next cleat. This construction is clearly illustrated in Figs. 3, 4 and 5, where it will be seen that the cleat of Fig. 4 has its base flange at one end bent upward as at C to form a socket, the upper edge of the vertical flange being of the same height throughout, which socket should be of course of a depth corresponding to the thickness of the base flanges. The next cleat coöperating with this, has its opposite end formed with a similar socket as shown in Fig. 5 so that it may similarly coöperate with the next cleat. In other words, the cleats with the sockets are formed "right and left," by reason of the peculiar manner in which they are assembled and coöperate on the rim of the wheel. Any appropriate means may be employed, such as by the use of rivets, for firmly attaching the base flanges to the wheel rim, but I have shown and I prefer to utilize for this purpose, the spokes of the wheel, which are extended through the wheel rim and through the overlapping ends of the cleats and headed down thereon to secure the parts together, as illustrated particularly in Fig. 3.

Referring to Fig. 2, it will be observed that the continuous traction rib or surface formed conjointly by the upright flanges, extends a slight distance outward at the points where the vertical flanges intersect. This I con-

sider a desirable feature, in that the tractive effect is increased. In order that this effect may be more pronounced, the construction shown in Fig. 6 may be employed, where it will be seen that the cleats are extended beyond their points of intersection nearly to the edge of the rim.

While I prefer to form the socket or bend in the base flange of the cleat, in order to preserve the same height or level of the traction surface as described, it will be understood that this is not essential, for good results may be obtained by omitting these depressions and forming the traction cleat of the same cross-sectional form throughout. Furthermore, it is not absolutely essential although preferable, that the cleats be arranged right and left in the manner shown, because good results may be obtained by other arrangements provided that the traction surface formed conjointly by the vertical flanges will extend zigzag and continuously around the wheel rim.

Having thus described my invention, what I claim is:—

- 25 1. In combination with a wheel rim, traction cleats each comprising a base flange and an upright flange, said cleats extending diagonally with their base flanges overlapping at the ends, and fastened to the rim of the wheel.
- 30 2. In combination with a wheel rim, traction cleats, each comprising a base flange and an upright flange, said cleats extending diagonally with the end of the base flange of one cleat seated on the base flange of the adjacent cleat, and fastened to the rim of the wheel.
- 35 3. In combination with a wheel rim, a series of traction cleats applied thereto and each comprising a base flange and an upright flange, said cleats extending diagonally with the base flange of one seated at one end on the base flange of one of its adjacent cleats, and having the other end of its base flange extended beneath the base flange of its other adjacent cleat.
- 40 4. In combination with a wheel rim, a series of traction cleats applied thereto and

each comprising a base flange and an upright flange, said cleats extending diagonally and each having its base flange formed in its under side at one end with a socket or bend adapted to receive the base flange of the adjacent cleat.

55 5. In combination with a wheel rim, a series of traction cleats applied thereto diagonally, and each comprising a base flange and an upright flange, the base flange of one cleat being seated at one end on the base flange of one of its adjacent cleats, and extending at its opposite end beneath the base flange of its other adjacent cleat, and each of said cleats, where it underlies the end of the other, being extended beyond the point of intersection.

60 6. In combination with a wheel rim, a series of traction cleats applied thereto diagonally and each comprising a base flange resting on the wheel rim and an upright flange, each cleat being seated at one extremity on the base flange of the next cleat, with its end abutting against the upright flange of said cleat.

65 7. In combination with the hub, spokes and rim, traction cleats applied diagonally to the rim with their ends overlapping, the said spokes being extended outward through the rim and through the overlapping ends of the cleats and acting to secure the said cleats in place.

70 8. In a traction wheel, a series of complementary traction cleats or elements, each comprising a base flange adapted to rest on and be secured to the rim of the wheel, and an upright flange adapted to form a traction rib, a portion of said cleats having a socket or bend formed in the base flange at one end, and the remainder of said cleats having a similar socket or bend formed in their base flange at the opposite end.

80 In testimony whereof I hereunto set my hand this first day of November, 1906, in the presence of two attesting witnesses.

EMIL EINFELDT.
